CLAIM

The ornamental design for a stand off for mounting a vehicle lamp, as shown and described.

DESCRIPTION

FIG. 1 is a Perspective View of a stand off for mounting a vehicle lamp showing my new design;

FIG. 2 is a Front View thereof;

FIG. 3 is a Rear View thereof;

FIG. 4 is a Left View thereof;

FIG. 5 is a Right View thereof;

FIG. 6 is a Top View thereof;

FIG. 7 is a Bottom View thereof; and,

FIG. 8 is perspective view thereof, showing the stand off for mounting a vehicle lamp in a condition of use.

The broken lines shown in the drawings illustrate environmental structure and form no part of the claimed design.
